UNITED STATES PATENT OFFICE.

MARTIN HUBBELL, OF MOUNT KISCO, NEW YORK.

CLEVIS.

SPECIFICATION forming part of Letters Patent No. 249,941, dated November 22, 1881.

Application filed May 11, 1881. (Model.)

To all whom it may concern:

Be it known that I, MARTIN HUBBELL, of Mount Kisco, in the county of Westchester and State of New York, have invented certain 5 useful Improvements in Clevises for Plows and other Implements, of which the following is a specification.

The object of my invention is to facilitate the adjustment of the clevis-ring in any desired position.

The invention consists in a clevis with a longitudinal groove in the inner edge of its end slot, and with a series of notches, forming teeth, in the opposite edge, this clevis being 15 pivoted in the ordinary manner to a plow-beam. The extremity of the latter is provided with a series of vertical grooves. The clevis and the ring are placed in the desired position, and are locked in the same by means of a key fitting in the slot of the clevis.

In the accompanying drawings, Figure 1 is a longitudinal elevation of my improved plow. Fig. 2 is a horizontal sectional view of the same on the line $x-x$, Fig. 1.

25 Similar letters of reference indicate corresponding parts.

The clevis A is of the ordinary shape, but has a longitudinal groove, B, in the inner edge of its end slot, C, and the outer edge of this 30 slot is provided with a series of notches, D D. A key or flat pin, E, with a knob or head, E', or a ring at the upper end, the width of which key is equal to the distance from the deepest point of the groove B to the outer edge of the 35 teeth between the notches D, fits into this slot C, the clevis being provided at the top and bottom with short slots to admit this key. A locking wire or strip of leather or other suitable latch, F, is attached to the clevis, and is 40 passed into an aperture near the upper end of the key to lock this key in the clevis. The

plow-beam G is provided at its end with a block, H, suitably attached to this beam, and provided in its outer rounded surface with a series of vertical grooves, J J, of the same width 45 as the grooves B of the clevis. The clevis is pivoted to the beam G by means of the pintle K in such a manner that the inner edge of the slot C will coincide with the outer edge of the end block, H, as shown.

50 The operation is as follows: The clevis-ring L is placed into the desired notch D, and the clevis is inclined laterally toward the beam as much as may be desired until the groove B of the clevis coincides with one of the grooves J 55 of the end block, H. The key E is then placed into the clevis, and as it passes through the grooves B and J it locks the clevis in the position it has at the time. As the key fills the slot in the manner described, it also locks the 60 clevis-ring L in the notch in which it was at the time the key was inserted.

Having thus fully described my invention, I claim as new and desire to secure by Letters Patent—

65 1. The combination, with the clevis A, provided with a longitudinal groove, B, in the inner edge of its slot C, and with notches D in the opposite edge, of the plow-beam G, of the clevis-ring L, and the key E, substantially as 70 herein shown and described, and for the purpose set forth.

2. The combination, with the clevis-beam G, with grooves J in its front end, of the clevis with a groove, C, and notches D in the edges 75 of its slot, the key E, the ring L, and latch F, substantially as shown and described.

MARTIN HUBBELL.
